UNITED STATES PATENT OFFICE.

JOHN P. CLUETT, OF NEW YORK, N. Y.

DESIGN FOR A CASING FOR A HEATING APPLIANCE.

Application filed May 23, 1925. Serial No. 13,541. Term of patent 3½ years.

To all whom it may concern:

Be it known that I, JOHN P. CLUETT, a citizen of the United States, residing at 920 Riverside Drive, New York city, New York, have invented a new, original, and ornamental Design for Casing for a Heating Appliance, of which the following is a specification, reference being had to the accompanying drawing, forming part thereof.

In the drawing:

Figure 1 is a top plan view of the casing for a heating appliance; and

Figure 2 is a rear view of the casing for a heating appliance.

I claim:

The ornamental design for a casing for a heating appliance, as shown.

JOHN P. CLUETT.
